UNITED STATES PATENT OFFICE

1,993,818

PANTOGRAPHIC MECHANISM FOR
GRADING MACHINES

Hilmer Gustav Adolf Åkerlind, Stockholm, Sweden, assignor to Aktiebolaget Linham, Stockholm, Sweden

Application December 27, 1932, Serial No. 649,062
In Germany June 30, 1932

10 Claims. (Cl. 33—23)

In well-known grading machines which are employed especially in the shoe making industry, in order from a model for a shoe part or prototype, to produce whole series of similar patterns of all lengths and width measurements desired, independent power transmission means constructed to act in a pantographic manner are provided in order to effect a magnification or reduction in two directions, perpendicular to each other. Well-known machines of this type, however, suffer from the drawback that, at a constant adjustment of the machine, the magnification or reduction will be different according as the operation takes place at different points of the model supporting table, that is, the table on which the model is held, and, as a rule this variation will be the larger, the more the element or feeler moved against the periphery of the model is removed from the middle point of the table. By reason of this fact, it was hitherto necessary, during the operation, to hold the model in the middle of its supporting table and take care of not moving the feeler out to the circumference of the model supporting table, in order to avoid an undesired distortion of the graded patterns. In some of the machines now in use, the connecting rods and levers of the pantographic mechanisms are very long in order to suppress or reduce said fault, but it is never possible in this way to completely remove the fault and, furthermore, said long rods and levers must be very strong in order that they shall not be flexible to an undesired degree which would give rise to further faults. As a result, the machine becomes bulky and heavy, expensive in manufacture and difficult to attend.

The present invention has for its object to overcome the above said difficulties by the provision of a pantographic mechanism, by means by which it will be possible to produce, even in case of short, light connecting rods and levers, a good, distortionless, geometrically exact grading at all points of the model supporting table, that is, also at the circumference thereof. In other words, the grading by means of this mechanism will be independent of the position of the model following element or feeler on the model supporting table at unchanged adjustment of the machine, so that the model may be positioned at any point desired of its supporting table, and yet exactly the same result will be obtained. The adjustment into the middle of the working table necessary in connection with the well-known grading machines may be completely dispensed with, and the grading will be performed, at un-

changed adjustment, without distortion when operating near the circumference of the table.

Another object of the invention is to simplify the necessary scales used in effecting the adjustment for the size of the model as well as those used in performing the length and width grading of the product to be produced (as a pattern) so that the operation of the machine will be rendered much easier and much simpler than heretofore. The simplification of the scales may be realized by the special design of the pantographic mechanisms.

In the accompanying drawing, an example of a grading machine including pantographic mechanisms according to this invention is illustrated. Fig. 1 is a side elevation of the machine, and Fig. 2 is a top plane view thereof.

For the sake of simplicity, the invention will be hereinafter described as applied to a grading machine of the character set forth in the copending application, Serial Number 649,109 filed December 27, 1932. It is to be noted, however, that I do not intend to limit the use of my invention to such a machine, as the invention may be applied equally well to grading machines of different designs without departing from its scope or principle.

With reference to the drawing, the numeral 1 indicates the rigid frame of the machine which carries two guide tracks 2 and 3 on which runs a beam 4, as on rollers, which extends perpendicularly to the direction of said tracks. On this beam travel two carriages 5, 6 in the longitudinal direction of the beam. The carriage 5 carries a punch device 7 driven by an electric motor 8, and the carriage 6 carries a model tracing element or feeler 9 adapted to be moved against the outline of the model. A piece of cardboard or the like is to be clamped in the holder 10, and from this piece the graded patterns are to be cut out by means of the punch 7. The prototype or model is to be clamped to the table 11 by appropriate means (not shown). The table 11 travels back and forth in straight guide ways 12 rigidly secured to the frame 1, which extend perpendicularly to the beam 4. The carriage 6 is provided with a grasping handle 13 to facilitate moving the feeler 9 against the outline of the model.

A connecting bar 14 is pivoted at its one end to the carriage 6, as shown at 15, and at its other end, as indicated at 16, to a slide 17 slidably mounted on a lever 18 which may rotate about the pivot stud 19. The pivot stud 19 is attached to a slide 20 which engages a corresponding groove or recess formed in the carriage 5 so as to

allow relative adjustment of said carriage and said slide in the longitudinal direction of the beam 4. The slide 20 may be held in any position desired with relation to the carriage 5 by means 5 of the clamping screw 21. Thus, in operation, the pivot stud 19 is rigidly connected to the carriage 5. The other end of the lever 18 is pivoted, as indicated at 22, to a second lever 23 the other end of which is slidably mounted in a diametrical 10 opening or boring formed in a pivot stud 24. Said pivot stud 24 is rotatably, but not slidably, mounted in an arm 4a laterally projecting from the beam 4. The angular position of the levers 18 and 23 with respect to each other may be 15 adjusted by means of a clamping screw 25 the bolt of which engages a slot 26 formed in the lever 23.

The connecting bar 14 is provided with a scale 27 and carries a slide 28 which may be moved 20 over said scale. The adjustment of the slide 28 may be read off at 29. The angular position of the connecting bar 14 with respect to the longitudinal direction of the carriage 6 may be adjusted and fixed by means of a clamping screw 25 25 embracing the edge of a disk 31 attached to the carriage 6. Said disk 31 is provided with a scale 32. Attached to the slide 28 is a segment 33. The reading on the scale 32 takes place at the segment 33, inasmuch as this segment contacts with that division of the scale according 30 to which the grading of the model is taking place.

The beam 4 supporting the carriages 5 and 6 and the table 11 adapted to support the model 35 are connected together by a pantographic mechanism similar to that connecting the carriages 5 and 6. To this end, the laterally extending arm 4a of the beam 4 carries a pivot stud 34 which is rotatably, but not slidably, mounted in 40 said arm 4a. Slidably mounted in a diametrical extending boring in said pivot stud 34 is a lever 50 pivoted at its other end to a lever 51 and provided with a clamping screw 52 the bolt of which engages a slot 53 formed in the lever 50 45 to allow adjustment of the angular position of the levers 50 and 51 with respect to each other. The lever 51 is pivoted, at 54, to a lateral projection 55 of the frame 1 and carries at its end remote from the lever 50 a slide 56, to which there 50 is pivoted, at 57, a connecting bar 58 pivoted at its other end, at 59, to the under side of the model supporting table 11. The connecting bar 58 is provided with a scale 60 and carries a slide 61 which may be moved over said scale.

The angular position of the connecting bar 58 55 with respect to the direction of movement of the table 11 may be adjusted and fixed by means of a clamping screw 62 embracing the edge of a disk 63 attached to the table 11. To facilitate 60 said adjustment the disk 63 is provided with a scale 64 the divisions of which extend in said direction of movement. The reading on the scale 63 takes place at a segment-shaped projection 64 of the slide 61.

The operation of the mechanism described is 65 as follows:

Let it be assumed that the levers 18 and 23 are held by the clamping screw 25 in their normal relative position, that is to say, so that they 70 are in line with each other. When, for instance, the connecting bar 14 is adjusted to the position shown in Fig. 2, and is held there by means of the clamping screw 30, i. e. so that the pivot 16 is below the pivot 19, as seen in this figure, then 75 the movement (or the component of movement)

of the feeler 9 in the direction of the beam 4 will be transmitted to the carriage 5 and the punch 7 on a reduced scale. As the pivot 16, after having been thus adjusted will move in a path parallel to the beam 4, the transmission at all points of the path of the feeler 9 along the beam 4 will be exactly pantographic, that is, any change of the scale which would cause a distortion cannot take place. In other words, the movement of the punch 7 in the direction of the beam 4 at 10 a given adjustment of the machine will always be exactly proportional to the movement of the feeler 9 in the same direction. If, however, the pivot 16 be adjusted by means of the clamping screw 30 to a position between the pivots 19 15 and 22, then the movement of the feeler 9 in the direction of the beam 4 will be transmitted to the punch 7 proportionally magnified. With the pivots 16 and 19 in register with each other, the transmission will take place without any 20 magnification or reduction, that is, the distance between the punch 7 and the feeler 9 will remain constant.

As to movements in the direction of the guide tracks 2 and 3, the machine operates in a similar way to that above described, though the magnification or reduction will now be controlled by the other pantographic mechanism. When the feeler 9 is moving in an oblique direction with relation to the directions, as represented 30 by the guide tracks 2, 3 and the beam 4, respectively, the movement of the punch 7 is composed of the magnified or reduced, or unchanged components of movement in the two main directions in an well-known way. A change of the ratio 35 at certain points of the model may be effected at an unchanged adjustment of the connecting bar 14, by varying the angular position of the levers 18 and 23 by means of the clamping screw 25, in a well-known manner.

If, for instance, the scales 27 and 32 are used in effecting the length grading, then the slide 28 is to be adjusted in such a way that the reading edge or line at 29 will be in register with that division of the scale 27 which corresponds to the number of the model pattern. If, for instance, the model is of the shoe size No. "30", then the reading line 29 is to be adjusted into register with the division "30" of this scale. If now the pivot 16 be adjusted into register with the pivot 19, then the grading will give as result a graded pattern of the size No. "30". The corresponding division of the scale 32 which by that time is engaged by the segment 33 will, thus, represent the zero line of this scale. If it is now desired to grade complete series of patterns, then the arm 14 should first be adjusted to the next reducing division of the scale 32 (as read off at the segment 33) whereby a pattern of the size No. "29" will be obtained. In a similar way it is possible by adjustment of the arm 14 50 by means of the clamping screw 30 to produce all sizes available.

In grading exceptionally big or small patterns, the slide 28 may be adjusted to another division of the scale 27, and the grading may then be effected while the slide remains in this position. If, for instance, the model is of the size No. "30", then such extraordinary patterns may be graded while using the same model by adjusting the slide 28, for instance, on to the division "45", or to the division 25 of the scale 27, according as exceptionally small or big patterns are to be produced.

When, at a certain adjustment of the pantographic mechanism, a pattern has been cut, it will be possible, while said adjustment still re- 75

mains, to cut another or a plenty of other patterns from the same cardboard piece. To this end, the clamping screw 21 is to be unscrewed, and then the carriage 5 is to be moved into a position as far from its preceding position as to allow the punch to treat another part of the cardboard piece, without requiring any displacement of the cardboard piece. By displacement of the carriage 5 with relation to the slide 20 it is also possible, from the very beginning, to adjust the punch 7 into such a position with relation to the cardboard piece as to permit cutting of the graded patterns at the most convenient portions of the cardboard piece, in order that the cutting may take place with the waste of material reduced to a minimum. By this reason, the operation will, consequently, be considerably facilitated.

As the scales 27 and 32 are very simple, the adjustment will be simple, and the risk of errors reduced to a minimum. This circumstance and the simplicity of the mechanism as a whole, and the correct, distortionless work, regardless of the position of the feeler with relation to the model supporting table, represent great advantages over against well-known grading machines.

The construction described, and illustrated in the drawing may be changed in several respects without departing from the principle or scope of the invention. Means well-known in connection with grading machines may also be used in connection with the device forming the subject matter of this invention, though such means are not illustrated in the drawing for the sake of clearness. The pivot stud 19 may, of course, be attached directly to the carriage 5. The lever 23 may only be rotatable about the pivot stud 24, but not slidable, in which case the lever 18 must be slidable with relation to the stud 19. An indispensable feature is that one of the members movable in the respective main direction which are to be connected by the pantographic mechanism must carry a rotatably mounted slide, the axis of rotation of which after having been adjusted will always move parallel to the said main direction, whereas the other member and a further member, which is held against movement during the movement in the respective main direction, each carry a rotary pivot stud, a rod or lever being mounted to turn about both of these pivot studs, said rod having a straight portion which is also in slidable engagement with one of said pivot studs and having a further straight portion, on which travels the slide.

The pantographic mechanism according to the invention may, of course, be used even in connection with grading machines, in which said pantographic mechanism is employed to effect the grading in one main direction only, while as far as the other main direction is concerned, a pantographic mechanism of hitherto known design is provided, in which case, however, a distortionless grading will be obtained only in that direction, in respect of which the pantographic mechanism according to the invention operates.

In the appended claims the carriages 5 and 6, the beam 4 and the model supporting table are referred to by the term "element" to "elements".

What I claim is:—

1. In a mechanism of the character described, two elements movable with respect to each other in a direction, an arm pivoted to one of said elements, means to adjust said arm to different angular positions with relation to the respective element, a slide pivotally connected to said arm, a lever to slidably engage said slide, a pivot to con-

nect said lever to the other element, and another pivot to afford a fulcrum for the lever which is immovable with respect to the direction of movement of the elements. 5

2. In a mechanism of the character described, two elements movable with respect to each other in a direction, an arm pivoted to one of said elements, adjustable to different angular positions with respect to the direction of movement of the element, a scale on this element to facilitate said adjustment, a scale on the arm, slidable means on the arm to point on both of said scales, a slide pivoted to the free end of the arm, a lever in slidable engagement with said slide, a pivot to connect said lever to the other element, and another pivot to afford a fulcrum for the lever which is immovable with regard to the direction of movement of the elements, the lever being in slidable engagement with one of said pivots. 10

3. In a mechanism of the character described, two elements movable with respect to each other in a direction, an arm pivoted to one of said elements, adjustable to different angular positions with respect to the direction of movement of the element, a scale on this element to facilitate said adjustment, a scale on the arm, slidable means on the arm to point on both of said scales, a slide pivoted to the free end of the arm, a lever in slidable engagement with said slide, a member in slidable engagement with the other element and adjustable with respect thereto in the direction of movement of the element, a pivot to connect the lever to said member, and another pivot to afford a fulcrum for the lever which is immovable with regard to the direction of movement of the elements, the lever being in slidable engagement with one of said pivots. 15

4. In a mechanism of the character described, two elements movable with respect to each other in a direction, an arm pivoted to one of said elements, adjustable to different angular positions with respect to the direction of movement of the element, a scale on this element to facilitate said adjustment, a scale on the arm, slidable means on the arm to point on both of said scales, a slide pivoted to the free end of the arm, a lever in slidable engagement with said slide, a member in slidable engagement with the other element and adjustable with respect thereto in the direction of movement of the element, a pivot to connect the lever to said member, and another pivot to afford a fulcrum for the lever which is immovable with regard to the direction of movement of the elements, one of said pivots being formed with a boring to be slidably engaged by the lever. 20

5. In a mechanism of the character described, a beam movable back and forth in a transverse direction, two carriages on said beam movable with respect to each other in the longitudinal direction of the beam, a model following element on one of said carriages and a work treating element on the other carriage, an arm pivoted to one carriage adjustable to different angular position with respect to the direction of movement of the carriage, a scale on this carriage to facilitate said adjustment, a scale on the arm, slidable means on the arm to point on both of said scales, a slide pivoted to the free end of the arm, a lever in slidable engagement with said slide, a member in slidable engagement with the other carriage and adjustable with respect thereto in the direction of movement of the carriage, a pivot to connect the lever to said member, another pivot to connect the lever to the beam, said last- 25

mentioned pivot being formed with a boring to be slidably engaged by the lever, a table movable back and forth in the direction of movement of the beam, and means to transmit movement at 5 a variable ratio of transmission between said table and said beam.

6. In a mechanism of the character described, elements arranged for relative movements in pairs in more than one direction, an arm pivoted to one of the elements of each pair of elements, means to adjust the angular position of said arm with relation to the direction of movement of the respective pair of elements, a slide pivoted to said arm, a lever in slidable engagement with the 10 slide, a pivot to connect said lever to the other element of the respective pair of elements, and another pivot adapted to afford a fulcrum for the lever which is immovable with regard to the direction of movement of the respective pair of 15 elements, the lever being in slidable engagement with one of said pivots.

7. In a mechanism of the character described, two elements movable with respect to each other in a direction, and means to connect said elements to each other including a lever mounted to swing about a pivot and two other pivots so arranged in connection with said lever and with each of said elements that upon the swinging of the lever about said first-mentioned pivot said 20 two other pivots move parallel to the direction of movement of said elements and move said elements accordingly.

8. In a mechanism of the character described, two elements movable with respect to each other in a direction, and means to connect said elements to each other including a lever mounted 25

to swing about a pivot and two other pivots so arranged in connection with said lever and with each of said elements that upon the swinging of the lever about said first-mentioned pivot said two other pivots move parallel to the direction of movement of said elements and move said elements accordingly, said lever being in slidable engagement with two of said pivots. 5

9. In a mechanism of the character described, two elements movable with respect to each other in one direction, and means to connect said elements to each other including a lever mounted to swing about a pivot stationary with relation to the direction of movement of said elements, two other pivots so arranged in connection with 10 said lever and with each of said elements that upon the swinging of the lever about said first-mentioned pivot said two other pivots move parallel to said direction and move said elements accordingly, and means for effecting a variation 15 of the distance between said other pivots at right angles to said direction of movement.

10. In a mechanism of the character described, elements movable in pairs in more than one direction, a pantographic device to connect the 20 elements of each pair, each of said devices including a lever mounted to swing about a pivot and two other pivots so arranged in connection with said lever and with each of said elements that upon the swinging of the lever about said 25 first-mentioned pivot said two other pivots move parallel to the direction of movement of the respective elements and move said elements accordingly.

HILMER GUSTAV ADOLF ÅKERLIND.
